DESIGN FOR A BILLFOLD

Philip Wege, West Bend, Wis., assignor to Amity
Leather Products Co., West Bend, Wis., a corporation of Wisconsin

Application September 9, 1937, Serial No. 71,526

Term of patent 7 years

To all whom it may concern:

Be it known that I, Philip Wege, a citizen of the United States, of West Bend, in the county of Washington and State of Wisconsin, have invented a new, original, and ornamental Design for a Billfold, of which the following is a specification, reference being had to the accompanying drawing, forming part thereof.

In the drawing:

The edge portions shown in full lines are continued throughout the edges of the billfold.

I claim:

The ornamental design for a billfold, as shown and described.

PHILIP WEGE.
